UNITED STATES PATENT OFFICE.

HARRY D. HILDEBRAND, OF MOUNT VERNON, OHIO; ZAIDEE S. HILDEBRAND ADMINISTRATRIX OF SAID HARRY D. HILDEBRAND, DECEASED.

VALVE.

Application filed May 17, 1920. Serial No. 381,908.

To all whom it may concern:

Be it known that I, HARRY D. HILDEBRAND, residing at Mount Vernon, in the county of Knox and State of Ohio, a citizen 5 of the United States, have invented or discovered certain new and useful Improvements in Valves, of which improvements the following is specification.

In Letters Patent No. 1,229,456, granted 10 June 12, 1917, is described and shown a construction of valve mechanism having in combination oppositely disposed valve seats having ports therethrough and valves consisting of resilient metal strips which were 15 so supported by abutments in operative relation to the ports that the strips could be bent or flexed by the pressure of fluid to permit of escape of fluid through the ports. In one of the constructions shown in said 20 patent, the supporting abutments were arranged adjacent to the ends of the strip and the opening flexure of the spring was intermediate such abutments. In another form 25 the supporting abutment is arranged to bear against the strips at points approximately midway their lengths so that the opening of the valve is due to the flexure of the strip on opposite sides of the abutments.

The invention described and claimed 30 herein has for its object a construction of valve mechanism, in which the valves are maintained in normal or closed position by a suitably constructed and arranged resilient means, and the opening of the port is effected by substantially equal movement of the strip for its entire length against such pressure or by such equal movement and more or less flexure of the strip forming the valve. The invention is hereinafter 35 more fully described and claimed.

In the accompanying drawing forming a part of this specification, Fig. 1 is a top plan view showing the improvement embodied in a valve mechanism for an air or gas compressor; Fig. 2 and Fig. 3 are sectional views on planes indicated respectively by the lines II-II and III-III, Fig. 1; Figs. 4, 5, 6, 7 and 8 are diagrammatic views of different arrangements and constructions of springs.

In the practice of the invention, the metal strips 1 and their controlling spring or springs 2 are arranged in grooves 3 in the block 4 which may be of any peripheral contour, and the grooves may be parallel as

shown herein or radial as shown in the patent herein before mentioned. The ribs 5 intermediate of the grooves are made hollow for the flow of gas, air or other flows to the ports 6 formed in the side wal's of the ribs 60 as shown in Fig. 3.

The valves consist of metal strips which are yieldingly held in their respective seats by means of a spring 2 which may be semi-elliptical in shape or of any other desired 65 shape or construction. As shown, the spring or springs are arranged intermediate the valves and bear upon both valves. As for example, in the construction shown in Figs. 1, 2, and 3, the ends of the spring bear 70 on one valve or strip at points adjacent to its ends and on the opposite strip at a point intermediate its ends. The strip of metal forming the valves may be made with such a rigidity relative to the spring that the entire movements of the valves are due to a yielding of the spring, or if desired, the strips may be resilient and sufficiently yielding that the opening of the port is due in 75 part to the flexure of the strip itself. 80

In lieu of a single spring as shown in Figs. 1, 2, and 3, two springs may be interposed between the valve strips as shown in Figs. 4, 5, 6, 7 and 8.

In the construction shown in Fig. 4 the 85 springs are arranged to bear at their ends in the strips and against one another at a point intermediate the ends while Fig. 8 shows a reversed arrangement of the springs, the springs being in contact with 90 the valve at points intermediate their ends, while the latter are in contact. In the construction shown in Fig. 6, two springs are employed, each bearing at their ends on one strip or valve, and at an intermediate point 95 on the opposite strip or valve.

In lieu of elliptical springs other shapes or constructions of springs may be employed without departing from the spirit of the invention described and claimed 100 herein. As for example, two substantially U-shaped springs as 2^a may be so arranged intermediate the valves that their ends will bear on the respective valves, as shown in Fig. 5. In order to prevent the springs 2^a 105 being tipped from operative positions, they are forced with eyes *a* engaging pins 8 projecting from the bottoms of the grooves 3.

As shown in Fig. 7, spiral springs 2^b may be employed. The eyes of the spiral are 110

slipped onto pins 9 in the bottoms of the grooves 3, while the outer members or coils of the spiral have diametrically opposite points in contact with the respective valve strips.

It is characteristic of the construction shown herein that the resilient means interposed between the valve strips is operative on both valves. This characteristic is found in the form shown in Fig. 4 and Fig. 8, for although neither spring is in direct engagement with both valves, the springs have their ends or points intermediate the ends in contact so that each valve is controlled by both springs.

I claim herein as my invention:

1. A valve mechanism for pumps, etc., having in combination two oppositely disposed valve seats having ports therethrough, 20 flat strips of suitable material for closing the ports, both side edges of said strips being free to move substantially equal distances from the seats and a spring for yieldingly holding said strips against the valve 25 seats.

2. A valve mechanism for pumps, etc., having in combination two oppositely dis-

posed valve seats having ports therethrough, metal strips for closing said ports, the side edges of said strips being free to move substantially equal distances from the seats and resilient means interposed between the valve strips for yieldingly holding said valves against the seats.

3. A valve mechanism for pumps, etc., 35 having in combination two oppositely disposed valve seats having ports therethrough, metal valve strips for closing said ports, both side edges of said strips being free to move substantially equal distances from the 40 seats and a spring adapted to bear against both strips for yieldingly holding the same against the respective seats.

4. A valve mechanism for pumps, etc., 45 having in combination two oppositely disposed valve seats having ports therethrough, resiliently flexible metal strips for closing said ports and resilient means interposed between the strips for holding them against the seats.

In testimony whereof, I have hereunto set my hand.

HARRY D. HILDEBRAND.
